US0D1059270S

(12) **United States Design Patent** (10) **Patent No.:** **US D1,059,270 S**
(45) **Date of Patent:** **** Jan. 28, 2025**

(54) **CHARGING STAND**

(71) Applicant: **Target Brands, Inc.**, Minneapolis, MN (US)

(72) Inventors: **Yousin B. Smith**, Flagstaff, AZ (US); **Daniel C. Rose**, Minneapolis, MN (US); **Kent D. Katterheinrich**, Shoreview, MN (US); **Nathan J. Romportl**, Richfield, MN (US); **Tyler J. Abrahamson**, Apple Valley, MN (US); **Nick E. Peters**, Minneapolis, MN (US)

(73) Assignee: **Target Brands, Inc.**, Minneapolis, MN (US)

(**) Term: **15 Years**

(21) Appl. No.: **29/822,998**

(22) Filed: **Jan. 13, 2022**

(51) LOC (15) Cl. **13-02**

(52) U.S. Cl.

USPC **D13/107**

(57)

CLAIM

The ornamental design for a charging stand, as shown and described.

DESCRIPTION

FIG. 1 is a front perspective view of a first embodiment of the charging stand showing our new design;

FIG. 2 is a back perspective view thereof;

FIG. 3 is a front view thereof;

FIG. 4 is a back view thereof;

FIG. 5 is a top view thereof;

FIG. 6 is a bottom view thereof; and,

FIG. 7 is a right side view thereof.

The broken lines are included for purposes of illustrating portions of the charging stand and form no part of the claimed design.

1 Claim, 6 Drawing Sheets
